UNITED STATES PATENT OFFICE

WILLIAM H. KELSEY, OF CLEVELAND, OHIO

IRONING DEVICE

Application filed July 5, 1929. Serial No. 376,064.

This invention relates to ironing devices of that form in which the ironing member or surface has rolling motion with relation to the material being ironed, its object being to provide an improved ironing member or surface which travels easily over the surface to be ironed and produces improved ironing results by the repeated application to the work of a succession of like ironing members.

10 A further object of the invention is to provide an ironing device including a plurality of rolling ironing members lying closely adjacent to each other and suitably heated so as to progressively smooth or iron the work with repeated effects at the several rolling members, such device being adaptable for a wide variety of uses, including hand irons, sadirons and the like.

20 Further objects of the invention are in part obvious and in part will appear more in detail hereinafter.

In the drawings, Fig. 1 is a bottom plan view of one form of sadiron embodying the 25 invention, parts being broken away and in section to expose underlying parts; Fig. 2 is a cross section on the line 2—2, Fig. 1; Fig. 3 is a side elevation of a part of the iron; Figs. 4 and 5 are detail cross sections corresponding to Fig. 2 and illustrating modifications; Fig. 6 is a detail section on the line 30 6—6, Fig. 5; Fig. 7 is a detail bottom plan view illustrating another modification; Fig. 8 is a detail section corresponding to Fig. 2 and illustrating electrically heated rollers; and Fig. 9 is a detail sectional view illustrating the invention applied to a larger ironing machine.

According to my invention, I provide any 40 form of ironing device, such as a roll, platen, hand iron or the like, with a plurality of relatively small rolling members which lie closely adjacent to each other to form a more or less continuous surface and which members, when cylindrical, will lie parallel or be arranged in groups of parallel members. The usual smooth and unbroken ironing surface of the ordinary gas heated hand iron, electrically heated sadiron, or the heavy roll 45 or platen in a larger ironing machine, ac-

cording to my invention, is replaced by or provided with a surface formed of a suitable number, usually ten, twenty or even a much larger number, of small rod-like rollers lying parallel and closely adjacent and extending cross-wise of the direction of travel of the iron along the work or the work along the iron, as the case may be, so that relative movement between them is accomplished with comparative ease, all of the rollers being 55 heated and exerting their individual ironing effects upon the work. The small rollers may be made of any suitable material having a smooth surface, even glass or composition materials, although heat conducting material, such as one of the metals like steel, iron, copper, or brass, may be more suitable. Balls may be used in certain cases and the rolls or balls may be of various sizes and lengths and may even be sectional, such as in 60 the form of a series of thimbles or short sleeves supported end to end upon the same axis.

Figs. 1 and 2 show the invention applied to an electric sadiron, part only of which is 65 shown. It comprises a heavy metal base or body 1 heated upon its upper face by the electric resistance wires 2 enclosed in the usual shield or casing 3, said wires being strung on suitable insulating supports, such as the mica spacers 4, and the iron being provided on its bottom with a circumferential flange 5 forming a shallow recess 6 in which are located a series of ironing rollers 7. Said rollers extend transversely, as shown 70 in Fig. 1, and vary in length. They are all journalled or otherwise rotatably supported in the flanges 5 and lie closely contiguous to each other and to the surface of the body 1, but they are out of actual contact with each other or with said body, reducing the frictional resistance to travel to only that at the 75 journals.

Several journal arrangements are suitable. In Fig. 2, the rolls are provided with end sockets to receive pins 8 which are driven solidly by a driving fit into openings in the flanges 5. In Fig. 4 trunnions 8a are threaded into the rolls through similar openings in the flanges 5, while in Figs. 5 and 6 the flanges 5 have 80 85 90 95 100

inwardly extending portions 9 which are slotted longitudinally to form a continuous channel 10 into which pins or trunnions 8b on the rolls extend, the trunnions being separated by small blocks 11 loosely inserted into the channels and forming spacers to keep the rolls out of contact with each other. This iron is heated by a gas burner 25.

In Fig. 2 the flanges 5 are an integral portion of the body of the iron itself. In other words, the sadiron is especially built to receive the rolls. However, my ironing surface may be adapted to any ironing device as a separate attachment, and in Fig. 5 the flange 5 is part of a frame-work for supporting the rolls 7, said flanges being secured to the sides of an ordinary sadiron by the securing screws 12 in such position that the rolls 7 are just below its usual smooth ironing surface 13. These ironing rolls, in any of the forms shown herein, may be heated in any suitable manner, and in Figs. 2 and 4 they are heated by heat radiated from the body 1 as well as by conduction to the journals, and heat from both the rolls and body is effective upon the work. In Fig. 8, which for convenience shows a separate attachment to the body 1 of an ordinary iron, the roll holding frame, including the flanges 5, is formed somewhat after the fashion shown in Fig. 5, but the longitudinal channels in said flanges, marked 14, are made of proper size to contain conducting channel members 15 insulated from each other and from the flanges 5 and iron body by insulating material 16. The rolls 7a are hollow, each containing a suitable heating or resistance wire 17, which is suitably insulated from the roll such as by being imbedded in composition insulation, or by stringing wire upon mica spacers 19. The resistance wires are electrically connected to the journal pins 8c, which pass through insulating bushings and engage the conductors 15, one of which is connected to positive and the other to negative.

On all of these irons the rolls may be arranged in various ways. In Fig. 1 the rolls are all parallel and lie cross-wise. Fig. 7, however, shows them inclined to each other in two groups, with a consequent tendency to spread and stretch the work laterally in opposite directions and thereby improve the finish.

Fig. 9 shows the invention adapted to a large ironing machine including a stationary concave platen or chest 20 and a cooperating roll 21, either or both of which may be hollow and suitably heated such as by conducting steam through the chambers thereof. The surface of the chest 20 may be formed by a series of small rolls of the kind before described and here indicated at 7a. Roll 21 being padded, its rotation carries the work, such as a sheet or the like, past the several small rollers 7a for an efficient ironing thereeof.

Other arrangements embodying the invention will be apparent to those skilled in the art.

What I claim is:

1. In combination, an ironing member having a heated wall, and an ironing unit detachably connected thereto and provided with a plurality of rolling members lying closely adjacent thereto, said heated wall being provided with a smooth iron surface adapted for direct application to the work upon removal of said unit. 70

2. In combination, an ironing member having a heated wall, and an ironing unit detachably connected thereto and provided with a plurality of rolling members lying closely adjacent thereto, said rolling members being in two series, the members of each series being in parallel relation and the members of the two series being at an angle to each other. 80 35

In testimony whereof I hereby affix my signature.

WILLIAM H. KELSEY.
